(Cl. D63—1)

To all whom it may concern:

Be it known that we, Donald E. Beckett and William N. Beckett, citizens of the United States, residing at Wilmington, in the county of Clinton and State of Ohio, have invented a new, original, and ornamental Design for an Automatic Drill Press Feed or the like, of which the following is a specification, reference being had to the accompanying drawings, forming part thereof:

Fig. 1 is a side elevational view of an automatic drill press feed showing our new design, the opposite side being substantially like the side shown.

Fig. 2 is a front elevational view of the device of Fig. 1.

We claim:

The ornamental design for an automatic drill press feed or the like, as shown and described.

DONALD E. BECKETT.
WILLIAM N. BECKETT.
